UNITED STATES PATENT OFFICE.

CHARLES LOUQUE, OF NEW ORLEANS, LOUISIANA.

RECIPROCATING BALANCE FOR STEAM-ENGINES.

SPECIFICATION forming part of Letters Patent No. 350,068, dated September 28, 1886.

Application filed April 24, 1886. Serial No. 200,111. (No model.)

To all whom it may concern:

Be it known that I, CHARLES LOUQUE, a citizen of the United States, residing at New Orleans, in the parish of Orleans, State of Louisiana, have invented a new and useful 5 Reciprocating Balance for Steam-Engines, of which the following is a specification.

My invention relates to improvements in reciprocating balances for steam - engines, in 10 which reciprocating rods operate in conjunction with reciprocating counter-weights; and the objects of my improvements are, first, to prevent the vibration of an engine; second, to render a high piston speed possible. I attain 15 these objects by the mechanism illustrated in the accompanying drawings, in which—

Figure 1 is a front elevation, partly in section. Fig. 2 is a side elevation. Fig. 3 is a detailed view of the shaft with three cranks. Fig. 20 4 is a section on line $x x$, Fig. 2.

Similar letters refer to similar parts throughout the several views.

In the drawings I have shown my invention applied to an ordinary upright engine, F, representing the piston-rod connected to a cross-head, H, running in suitable guides on the engine-frame. Connected with this cross-head is the main connecting-rod P, fastened at its lower end to the crank G on the main crank-shaft C in the usual manner. This shaft is mounted on bearings near the base of the engine, and has upon the side opposite the main crank two smaller cranks, c c, with which are connected two smaller connecting-rods, R R, 30 one on each side of the crank-shaft, each having at its upper end the weights or metal blocks W, adapted to travel on suitable guides, S S, on the engine-frame, and running parallel with the main cross-head. The cranks c c, it 35 will be noticed, are on the same side of the shaft and opposite to the main crank G, so that as the latter is depressed the former will be elevated, and vice versa. These rods P and R R are connected to their respective cranks in the 40 usual way, the ordinary straps and keys being employed, and are also jointed to the weights in any suitable manner. The weights W W and the connecting-rods R R are so adjusted that they will just balance the weight of the 45 piston, piston-rod, and connecting-rod of the 50

engine, so that all the operating parts will be in a perfect running balance, the piston remaining in the middle of the cylinder when the engine is at rest with no pressure of steam upon it.

The operation of the device as already described will now be apparent. When the engine is at rest, the piston is midway of the cylinder by reason of the balancing of it and the connected parts by the weights and connecting-rods, so that steam admitted to either side will immediately start it, thus overcoming the difficulty of dead-centers. During its operation the weights opposing the piston will move in a direction opposite to that of the piston, 65 and acting in a measure as a fly-wheel effectually prevent the pounding and jar caused by the rapid reciprocation of the piston, and enabling the engine to be run at a very high speed without oscillating and pounding, as 70 is usual with engines not employing fly-wheels. For this reason my invention is especially adapted for use on boats, where immunity from jar is desirable. It also enables ordinary vertical engines to be used in boats, which 75 heretofore could not be done on account of this jar.

Engines constructed with my improvement applied thereto are very slightly more expensive than those now in use, while the advantages and capabilities are far greater, and enables the engine to be employed in places where it was impossible to do so before.

I do not desire to be confined to precisely the devices shown, as other equivalents of these 85 could be employed with equally good effect without departing from the spirit of my invention.

I claim as my invention—

1. In a steam-engine, the combination, with the main crank-shaft having cranks on opposite sides thereof, a piston connected to one of said cranks, and a reciprocating weight connected to the opposite crank, whereby the weight and piston will be moved in opposite 95 directions, substantially as described.
2. In a steam-engine, the combination, with the main shaft, the reciprocating piston connected thereto, and the reciprocating weights connected to said shaft on the side opposite 100

the piston, so as to move in opposition thereto, substantially as described.

3. In a steam-engine, the combination, with the main shaft having the three cranks, the 5 reciprocating piston-head and connecting-rod, of the two reciprocating weights, and their connecting-rods connected to the opposite side of the shaft from the main piston, so as to move in opposition thereto, substantially as described.

4. In a steam-engine, the combination, with the main frame having the three guideways, the 10 piston-rod, the main cross-head, connecting-rod, and crank-shaft, of the two reciprocating weights—one on either side—the cross-head 15 moving in the guides and connected to the main shaft on the side opposite the main connecting-rod, substantially as described.

5. In a vertical steam-engine, the combination, with the piston-head, piston-rod, cross-head and connecting-rod, the main crank-shaft to which the latter is connected, of the vertically-reciprocating weights connected to the crank-shaft so as to move in a direction opposite to the piston, so adjusted with all connecting parts as to balance the weight of the 20 piston-head, piston-rod, cross-head, connecting-rod, and connected joints, substantially as described.

CHAS. LOUQUE.
